(57) **CLAIM**

The ornamental design for a tool handle, as shown and described.

DESCRIPTION

FIG. 1 is a front elevation view of the tool handle in accordance with my invention;

FIG. 2 is a back elevation view of the tool handle;

FIG. 3 is a first side elevation view of the tool handle; the second side elevational view being a mirror image thereof;

FIG. 4 is a top plan view of the tool handle;

FIG. 5 is a bottom plan view of the tool handle;

FIG. 6 is a top-front-right perspective view of the tool handle; the top-front-left perspective view being a mirror image thereof;

FIG. 7 is a top-rear-right perspective view of the tool handle; the top-rear-left perspective view being a mirror image thereof;

FIG. 8 is a bottom-front-right perspective view of the tool handle; the bottom-front-left perspective view being a mirror image thereof; and,

FIG. 9 is a bottom-rear-right perspective view of the tool handle; the bottom-rear-left perspective view being a mirror image thereof.

The broken lines illustrated throughout the figures of the drawings do not form any part of the claimed invention.
